CLAIM

The ornamental design for a pillow travel bag, as shown and described.

DESCRIPTION

FIG. 1 is a top plan view of our new design for a pillow travel bag;

FIG. 2 is a bottom plan view of the bag shown in FIG. 1; FIG. 3 is a front side elevation view of the bag shown in FIG. 1;

FIG. 4 is a rear side elevation view of the bag shown in FIG. 1;

FIG. 5 is a left side elevation plan view of the bag shown in FIG. 1; and

FIG. 6 is a right side elevation view of the bag shown in FIG. 1.

FIG. 7 is a perspective view of the bag shown in FIG. 1, unzipped and opened.

FIG. 8 is a perspective view of the bag shown in FIG. 1, zipped and containing a pillow; and,

FIG. 9 is a perspective view of the bag shown in FIG. 8, rolled up with straps secured.

The broken lines showing a carrying strap, a zippered pocket, the N(GHT logo, and stitching along the edges of the retaining straps are included for the purpose of illustrating environmental structure only, and form no part of the claimed design.

The "N(GHT" logo forming part of the drawing disclosure is a registered trademark of Discover Night LLC.
